UNITED STATES PATENT OFFICE.

EDWARD WESTON, OF NEWARK, NEW JERSEY.

DEVICE FOR VENTILATING THE ARMATURES OF DYNAMO-ELECTRIC MACHINES.

SPECIFICATION forming part of Letters Patent No. 245,900, dated August 16, 1881.

Application filed June 14, 1880. (No model.)

To all whom it may concern:

Be it known that I, EDWARD WESTON, of Newark, New Jersey, have invented a certain Improvement in Devices for Ventilating the 5 Armatures of Dynamo-Electric Machines, of which the following is a specification.

My improvements relate to that class of dynamo-electric machines in which the rotating coils are wound upon a hollow core having 10 apertures in its ends and in its periphery for the purpose of cooling the armature and adjacent parts by the agency of currents of air, which, when the armature is rotated, are drawn into the interior of the core through the apertures in its ends and expelled by centrifugal force through the apertures in its periphery; and my present invention consists in providing fans or blowers, preferably within the hollow core, for the purpose of more effectually 15 maintaining currents of air through the apertures in the periphery of the armature.

Instead of arranging fans within or on the hollow core, I may combine them in various other ways with the hollow core and still attain the desired end.

The accompanying drawings, representing an armature embodying my invention, are as follows:

Figure 1 is a longitudinal section, showing 30 the end apertures and the apertures in its periphery. Fig. 2 is a transverse section through the line *x x* on Fig. 1.

I have not deemed it necessary to show all the parts of a dynamo-electric machine, as my 35 invention relates solely to the ventilating devices applied to the armature, and such machines are fully shown in Letters Patent of the United States Nos. 209,532 and 211,311, heretofore respectively granted to me October 29, 40 1878, and January 14, 1879.

The drawings represent an armature built up of thin iron perforated plates *a*, each of which is centrally perforated for application upon the armature-shaft *A*, and is otherwise 45 perforated to allow the circulation of air through the interior of the armature.

The plates shown in the drawings are in the form of cog-wheels, the rims of which, *a'*, are united to their hubs *a* by the two spokes *a²* *a³*.

The teeth *a⁴* are the polar extensions referred to in my patents before mentioned, the coils *C* of the armature being wound between the polar extensions, as shown.

The plates *a* are separated from each other by the collars *B*, each of which is provided 55 with two radially-projecting arms, *b*, which serve to fill the spaces between the adjacent spokes of the wheels, and which constitute, in connection with the edges of the spokes, the fans for throwing the air outward through the 60 apertures *D* in the periphery of the armature—that is, through the open spaces between the adjacent rims and polar extensions of the wheels, respectively.

The place of the air ejected from the interior of the armature by the centrifugal action of the fans is supplied by air drawn into the interior of the armature through the apertures *E* in its ends.

It is obvious that, in lieu of separate fans on 70 the several plates *a*, fans extending continuously through the whole series may be used.

It is also obvious that the fans may be dispensed with and the armature connected to an ordinary fan-blower or other apparatus, and 75 the air be thus forced through the armature.

I claim as my invention—

The combination, with an armature of a dynamo-electric machine having its coils wound upon a hollow core provided with holes or apertures in its ends and in its periphery, of a 80 blower or fan for more effectually causing currents of air to pass from the interior of the armature-core through the apertures of the periphery.

EDWARD WESTON.
